UNITED STATES PATENT OFFICE

ALPHONSE F. PIEPER, OF ROCHESTER, NEW YORK

DENTAL EQUIPMENT APPARATUS

Application filed May 6, 1925. Serial No. 28,484.

The present invention relates to dental equipment and, more particularly, to apparatus adapted to be supported by the pedestal of a dental chair, the object being to improve both upon the construction and arrangement of the equipment whereby it will be compact, efficient, economical to construct and convenient to operate.

A further object of the invention is to provide dental equipment stands or pedestals having equipment supporting arms adapted to swing one upon another and provided with improved fuel control means for a burner carried by one of the arms.

To these and other ends the invention resides in certain improvements and combinations of parts, all as will be hereinafter more fully described, the novel features being pointed out in the claims at the end of the specification.

In the drawings:—

Figure 1 is a fragmentary front elevation of a dental equipment stand embodying the present invention;

Figure 2 is a part sectional elevation on an enlarged scale showing the manner of mounting the fuel supply connections for the burner;

Figure 3 is an enlarged fragmentary sectional elevation taken centrally through the lower valve and pipe joint shown in Figure 2, and

Figure 4 is an enlarged fragmentary sectional elevation through the burner control valve and pivotal connection for the relatively movable arms shown in Figures 1 and 2.

Similar reference numerals throughout the several views indicate the same parts.

The embodiment of the invention disclosed herein, by way of illustration, comprises a hollow main supporting column or standard 10 of any preferred design, only a portion of which is shown, and from which projects a hollow extension or main arm or bracket 11 having a pivoted branch arm 12 for supporting the motor, not shown. An instrument tray or holder 13 of any preferred design is suitably mounted for adjustment on an arm 14 adapted to swing upon a somewhat longer arm 15 which is pivoted to swing about the

axis 16 of the stationary arm or bracket 11. A tubular member 17 forms a pivotal connection between the arms 14 and 15 and is preferably held rigid upon the latter by a set screw 18. The tubular member 17 carries a hollow extension 19 upon which is mounted any desired type of gas burner 20 preferably located adjacent the tray 13 as shown in Figure 1.

The pivoted arm 15 is preferably channel shaped and adapted to receive and conceal a fuel or gas supply pipe 21, the outer end of which is connected with the tubular pivot member 17 and adapted to discharge into a valve chamber 22 therein. A needle valve 23, preferably of the thrust type, is disposed within the chamber and adapted to regulate the flow of gas to the burner through the reduced outlet passage 24 and the supply passage 25 leading to the burner. The valve is prevented from turning preferably by a screw 26 having its inner end reduced and projected into a slot 27 formed upon the enlarged portion 28 of the valve, said portion having a threaded extension 29 as shown in Figure 4. The extension 29 is threaded into an operating extension 30 having a handle 31 suitably connected therewith for operating the same. The extension 30 is held against longitudinal movement in one direction by a member 31^a preferably screwed into the tubular pivot member 17 against an enlarged portion 32 on the valve operating member 30. The enlarged portion 32 is slightly smaller in diameter than the recess in which it operates and is held against inward movement by a shoulder 33 formed in the base of the tube 17. A fluid tight joint is provided around the valve operating stem by means of suitable packing 34 compressed by a sleeve 35 forming a bearing for the operating member 30, the sleeve being forced against the packing by a nut 36 shouldered at 37 to engage the sleeve as shown in Figure 4. The nut 36 also serves to prevent outward displacement of the pivotal member 17.

The rigid pipe 21 is connected at its inner end with a hollow member 38, the upper end of which is disposed in a recess 39 formed in a boss like portion 40 of the arm 15 as shown

in Figure 2. A fuel supply pipe 41 is adapted to discharge into the hollow member 38 through a suitable connection 42, the pipe and connection being supported by the hollow member 38 which is secured by a pin, not shown, extended into a groove 38^a formed therein. The pipe 41 at its lower end is provided with a substantially right angle portion 43 screwed into a head 44 having a tubular member 45 rotatably disposed in a casing 46, the axis of the tube 45 being coincident with the axis of rotation of the arm 15 as indicated by the dot and dash line 16. This construction permits the use of a rigid pipe line connection through from the column 10 to the burner 20, thus avoiding the usual flexible tubing provided for conveying the gas to the burner which is unsightly and less durable than the present form of construction. The tube 45 connects with a valve chamber 47 in the casing 46, which in turn connects with a supply pipe 48 extending upwardly through the column 10 from a suitable supply source not shown. The casing 46 is secured within a recess 49 formed in the stationary arm or bracket 11 preferably by a bolt 50. In order to accurately center the casing with the pivotal axis of the arm 15 the stationary arm 11 is provided, above the recess 49, with a horizontally disposed plate portion 51 through which is drilled an opening 52 which is properly aligned with the pivotal axis of said arm and adapted to receive an accurately turned portion 53 of the casing, said portion being closely fitted within said opening whereby lateral movement of the casing is prevented and the tube 45 held in perfect alignment with the pivotal axis of the arm 15. The casing 46 is preferably adapted to have an additional bearing as at 54 upon the vertical portion 55 of the arm 11. A fluid tight joint for the revoluble tube 45 is provided in the lower end of the casing 46 embodying suitable packing 56 surrounding the tube which is compressed by a sleeve 57 forming a bearing for the tube and secured by a nut 58 threaded upon the casing. The nut is provided with an inwardly extended portion 59 engaging a shoulder on the sleeve 57 whereby to actuate the latter. The casing 46 is provided with a hollow extension 60 in which is disposed a valve as shown in Figure 3, for closing the pipe 48 whenever desired, said valve and associated parts being preferably constructed similar to the one described above in connection with Figure 4 and given the same reference characters, so that further description of the same is not deemed necessary. The fuel supply pipes, valves and connections are advantageously disposed upon the motor supporting and tray holding arms of the unit and afford an economical arrangement which permits the tray and burner carrying arms to swing freely upon their pivots

without injury to said pipes and connections. Furthermore, it will be noted that the supply pipe 41, motor carrying arm 12, and tray and burner holding arm 15 all have a common axis about which they are adapted to swing, whereby one member, such as the arm 11, is utilized to form a support for all of said parts. 70

I claim as my invention:

1. In dental equipment apparatus, a standard, an arm pivotally connected therewith, a burner carried by the arm, a rigid fuel supply pipe for the burner secured upon the arm independently of its pivotal connection with said standard and having its inlet end depending from the arm and pivotally connected with the standard at a point beneath the arm whereby it is adapted to swing with the arm, and a second supply pipe connected with the first. 75

2. In dental equipment apparatus, a standard, a bracket secured thereon, an arm adapted to swing upon the bracket, a burner carried by the arm, a rigid fuel supply pipe having one end connected with the burner and the other pivoted below the arm upon the bracket to swing with the arm about the pivotal axis thereof, said pipe passing from the arm to the bracket independently of the pivotal mounting of said arm on said bracket, and a supply conduit connected with the last mentioned end of said pipe. 90

3. In dental equipment apparatus, a standard, a bracket secured thereon, an arm adapted to swing upon the bracket, a burner carried by the arm, a casing carried by the bracket independently of the pivotal connection between the arm and the bracket, a rigid fuel supply pipe having one end connected with the burner and the other rotatably disposed within the casing, and a fuel supply connection leading to the casing. 100

4. In dental equipment apparatus, a standard, a valve including a casing connected with the standard, an arm pivotally connected with the standard at a point spaced from said casing, a burner carried by the arm, a fuel supply pipe for the burner secured upon the arm and having its inlet end pivotally disposed within the casing and adapted to be rotated by the arm, a supply conduit connected with the casing, and a valve connected with the supply pipe adjacent the burner. 110

5. In dental equipment apparatus, a standard, a vertically disposed arm carried thereby, a second arm adapted to swing upon the first, a burner carried by said second arm, a fuel supply pipe for the burner including a portion fixed upon the second mentioned arm and another portion projecting therefrom exteriorly of the first mentioned arm and pivotally connected with the latter whereby to swing with the second mentioned 120 125 130

arm, and a supply conduit connected with said pipe.

6. In dental equipment apparatus, a standard, an arm pivotally connected therewith, a burner carried by said arm, a fuel supply pipe for the burner secured upon the arm and having its inlet end projecting therefrom, a casing supported by the standard with which said inlet end is pivotally connected, said casing being independent of such pivotal connection, a supply conduit connected with said casing, and a control valve for the supply pipe connected with the casing.

15 7. In dental equipment apparatus, a column, a bracket secured thereon, an arm adapted to swing upon the bracket, a motor support adapted to swing about the pivotal axis of the arm, a burner carried by the arm, 20 and a fuel supply pipe for the burner secured upon the arm having a portion rotatably disposed upon the bracket coincident with and spaced from the pivotal axis of the arm whereby to swing with the latter.

25 8. In dental equipment apparatus, a column, a bracket secured thereon, an arm adapted to swing upon the bracket, a motor support adapted to swing about the pivotal axis of the arm, a burner carried by the arm, 30 a tubular member secured upon the bracket with and spaced from its longitudinal axis coincident with the pivotal axis of the arm, and a fuel supply pipe for the burner secured upon the arm and having one end rotatably 35 disposed in said tubular member whereby said pipe is adapted to swing with the arm.

9. In dental equipment apparatus, a column, a bracket secured thereon, an arm pivoted upon the bracket, a motor support 40 adapted to swing about the pivotal axis of the arm, a table, an arm for supporting the table, a burner, and a fuel supply pipe for the burner including a portion adapted to form a pivot upon which the second mentioned arm is adapted to swing, and also a portion pivotally disposed upon said bracket whereby the first mentioned arm is adapted to swing relative to the bracket.

45 10. In dental equipment apparatus, a column, a bracket secured thereon, an arm adapted to swing upon the bracket, a second arm mounted upon the first, a table carried by said second arm, a burner, and a fuel supply pipe for the burner forming a pivot for the second mentioned arm and having its inlet end pivotally connected with the bracket independently of the first mentioned arm at a point below the latter.

50 11. In dental equipment apparatus, a column, an arm pivotally connected therewith, a burner disposed at one side of the arm, a fuel supply pipe for the burner including a portion projecting laterally from the arm, a table holding arm pivotally disposed upon 55 said laterally projecting pipe portion and

means mounted upon the column independently of the arm adapted to pivotally receive the inlet end of the pipe.

12. In dental equipment apparatus, a column, an arm pivotally connected therewith, 70 a burner disposed at one side of the arm, a fuel supply pipe for the burner including a vertically disposed portion upon the arm, the inlet end of the pipe being pivotally connected with the column independently of the arm, 75 a fuel control valve adjustable in said vertical portion, and a second arm pivotally mounted upon said vertically disposed pipe portion to swing relative to the first mentioned arm.

80 13. In dental equipment apparatus, a column, an arm projecting therefrom, a tubular member vertically disposed upon said arm, a burner connected with said tubular member, a fuel controlled valve adjustable within said tubular member, a second arm mounted to swing upon said tubular member, and a fuel supply pipe connected with the tubular member and having its inlet end connected with the column independently of said arms.

85 14. In dental equipment apparatus, a column, a vertically disposed arm carried thereby, a laterally extending arm mounted to swing upon the upper end of said vertically disposed arm, a tubular member mounted upon the first mentioned arm adjacent the lower end thereof with its longitudinal axis coincident with the pivotal axis of the laterally extending arm, a fuel supply pipe secured upon the laterally extending arm and having one end pivotally disposed within said tubular member, and a burner connected with the other end of said pipe.

90 15. In dental equipment apparatus, a standard, an arm pivotally connected therewith, a burner carried by the arm, a rigid supply pipe having its outer end connected with the burner and having a portion depending from the arm and provided with an inlet end pivotally connected with the standard below the arm, and means connecting the pipe with the arm.

105 16. In dental equipment apparatus, a standard, a vertically disposed arm thereon, a second arm adapted to swing upon the first mentioned arm, a burner carried by the second arm, a casing upon the first mentioned arm positioned below the pivotal connection of the second arm upon said first arm and a fuel supply pipe having its inlet end pivotally disposed within the casing and its opposite end connected with the burner.

115 17. In a dental equipment, a main support, a main arm extending sidewardly and upwardly therefrom, a branch arm pivoted to said main arm, a gas pipe in said main arm, a gas pipe in said branch arm, a gas coupling having a stationary member mounted on said main arm and connected with said main arm

gas pipe, said coupling having a movable member rotatable on an axis coincident with the pivot axis of said branch arm, a connecting pipe outside of said main arm and extending from said movable coupling member to the gas pipe in said branch arm, and a valve controlling the gas flow through said coupling.

18. In dental equipment apparatus, a standard, an arm pivotally connected therewith, a burner carried by the arm, a pipe coupling secured to the standard independently of the arm and below the point of connection of the arm with the standard, a pipe secured 15 to the arm and having an outer end connected with the burner and an inner end extending below the arm and rotatably connected with the coupling, a supply pipe leading to the coupling, a valve for regulating the volume of fluid discharging from the supply pipe to the first mentioned pipe and a second valve for closing the outer end of said first mentioned pipe.

19. In dental equipment apparatus, a column, an arm pivotally connected therewith to swing relative thereto, a fuel supply pipe connected with the arm including a portion projecting laterally from one side thereof, said pipe having an inlet end extending below the arm, means mounted upon the column below the arm in which the inlet end of said pipe is pivotally mounted, a burner on the laterally projecting portion of the pipe and a second arm pivoted to swing about the 35 axis of said projecting pipe portion.
